H. B. SETZLER,
APPARATUS FOR TREATING PETROLEUM DERIVATIVES,
APPLICATION FILED OCT. 29, 1915.

Patented Jan. 28, 1919.

2 SHEETS—SHEET 2.

Inventor:
Horace B. Setzler,

Robert J. Lawrence
Attorney.

UNITED STATES PATENT OFFICE.

HORACE B. SETZLER, OF COFFEYVILLE, KANSAS, ASSIGNOR TO THE NATIONAL REFINING COMPANY, OF CLEVELAND, OHIO, A CORPORATION OF OHIO.

APPARATUS FOR TREATING PETROLEUM DERIVATIVES.

1,292,966.

Specification of Letters Patent. Patented Jan. 28, 1919.

Application filed October 29, 1915. Serial No. 58,720.

To all whom it may concern:

Be it known that I, HORACE B. SETZLER, a citizen of the United States of America, residing at Coffeyville, in the county of Montgomery and State of Kansas, have invented certain new and useful Improvements in Apparatus for Treating Petroleum Derivatives, of which the following is a specification.

My invention relates to improvements in apparatus for treating petroleum derivatives, and more particularly to such apparatus as is adapted for the pressure distillation of those hydrocarbons having relatively high boiling points. In such distillation, carbon necessarily is separated out from the compound under treatment, and new hydrocarbons are formed, which are conducted forth in the guise of gases and liquids. It is primarily the object of my invention, to prevent any material deposit of such carbon upon the heated bottom sheets of the still or container, used for practising such pressure distillation.

My invention has for a further object, the continuing conduct or operation of the process, by reason of providing pressure apparatus for intermittently supplying additional volumes of the hydrocarbons to be treated, and pressure condensing apparatus for liquefying the newly formed hydrocarbon products. This operation may be automatically conducted, although the apparatus which is herein shown, is designed for manual actuation.

The accompanying drawings set forth, somewhat diagrammatically, apparatus embodying my invention, wherein:—

Figure 1 is a diagrammatic view in side elevation, partially broken away, showing apparatus adapted for the practice of my invention, and

Fig. 2 is a similar view in end elevation.

Fig. 3 is a fragmentary view in longitudinal section, partially broken away, showing the pressure still and its agitating or scraping apparatus.

Fig. 4 is a transverse sectional view of said still.

Fig. 5 is a similar view, showing a modification thereof, and

Fig. 6 is an enlarged fragmentary view illustrating another modification.

Fig. 7 is a fragmentary sectional view upon an enlarged scale illustrating the use

of two sets of abrading chains upon the helicoïd.

Throughout the drawings, similar parts are indicated by the same character of reference.

In Fig. 1, a brick-enclosed furnace is shown, wherein the firing-chamber 1, is separated by the bridge wall 2, from the combustion chamber 3, from which a flue 4, leads to a stack 5, for the purpose of carrying off the products of combustion. The furnace is provided with a firing door 6, through which fuel is passed into the furnace, while the heat from combustion, is applied to the bottom of the cylinder-still 7, which is set over and supported by front and rear end walls, of the furnace and the combustion chamber. The still is provided with manhole 8, a pressure gage 9, and a thermometer (not shown). A charging inlet pipe 10, enters the still at its top, near the front end; the charging being controlled by valve 11, through which oil is pumped by means of pump 12, receiving its supply from a tank (not shown). A vapor line 13, leaves the still near its rear end, and leads to a condenser-box 14, which contains condensing coils 15, and beyond the condenser box is a valve 16, connected to a pipe leading to the receiving tank 17; the purpose of which equipment is to carry off, condense and receive the products which distil over.

The still 7, is equipped with a rotating shaft 18, mounted in water-cooled stuffing boxes 19, and fitted with a pulley wheel 20. Inside the still, there is attached to the shaft, a helicoidal cleaner 21, of such diameter and length as to engage the entire heated inner periphery of the still 7. At the front and rear ends of said shaft respectively, are water pipes, 22, 22', leading from a source (not shown), and entering passages drilled in the ends of the shaft 18, a distance equal, at least, to the length of the shaft inside of the stuffing boxes. A discharge pipe 23, is attached to the still at its bottom, near the rear end, to which is connected outlet pipe 24, leading to valve 25, to a second condensing box 26, and thence through the pipes 27, inside the box, and out through a valve 28, to a receiving tank 29. A motor 30' furnishes the power for driving the pulley wheel 20, connected to shaft 18.

The operation of my improved device,

may well be described in connection with the treatment of gas oil, and it may be assumed that the pressure-still 7 is charged approximately to one-half its capacity, with such 5 oil, after which, valves 11, 16 and 25 are closed. Power is turned on the motor connected with gear wheel 20, which revolves the helicoidal scraper or cleaner inside the still. The still is heated by supplies of fuel 10 passed from time to time through the firing-door 6, into the combustion chamber 3, the products of combustion being directed against the bottom of the still, so that the temperature of the contained oil, rapidly 15 rises, until it has reached about 700° F., at which temperature the pressure begins to rise, and is indicated on the pressure gage 9.

By the time pressure has reached 100 pounds, the temperature will have risen to 20 approximately 730° F., at which temperature and pressure, carbon begins to split off from the heated hydrocarbons; thereby producing new hydrocarbon compounds dissimilar from the mass of gas oil, and having boiling 25 points of 80° to 350° F., and a Baumé gravity of 56 to 58 B. It will be evident to those skilled in the art, that compounds having boiling points of 80° to 350° F., cannot, by reason of their inherent physical properties, 30 remain in the still at the temperature referred to, hence they are permitted to pass out through the vapor line 13, and are condensed in the coil 15, and thence conducted to the tank 17, by control of the valve 16.

35 I have found that without the use of suitable cleaning, scraping, scouring or agitating means, carbon, at the instant it is freed from its previous combination; being of amorphous character, and settling out of 40 the mass of gas oil, seems to be attracted, or drawn to the heated bottom still sheets. Normally, these particles of carbon growing together and agglomerating over the bottom sheet, form a coating of carbon, of semi-crystalline form, which would have the 45 dangerous results hereafter explained. By using a helicoid cleaner, continuously revolving inside the still, and engaging the heated section of inner periphery of the 50 cylinder, or its equivalent, the carbon which has been freed from its combination, is kept in an amorphous condition, and suspended throughout the mass of oil. Any carbon, which by chance is attracted or becomes attached to the bottom, can not remain there, 55 because the blade of the helicoid engaging on the bottom, sweeps the particles of carbon away in its course of travel.

In other apparatus for pressure distillation, with which I am acquainted, no adequate provision is afforded for the elimination of the difficulty residing in the accumulation of carbon. Normally, this carbon becomes firmly attached to the bottom sheets 60 of the still, in increasing quantities, until

a sufficient layer thereof, has accumulated to make the operation of the still unsafe. This is because of the fact that the carbon inner coating, acts as a heat insulator, so that the bottom plates will become dangerously overheated, thereby contributing to the destruction of the still, and its contents. Accordingly, it is necessary, in any continuing process of pressure distillation, to make provision against this danger, and this I 70 have accomplished by the agitating, scouring and scraping means already described, and further detailed in the specification.

It is also apparent that with a still working under the conditions of pressure and 80 heat necessary to effect pressure distillation of hydrocarbons, utmost precautions must be observed for maintaining the hermetic seal of the still. The vulnerable point or points of the still herein described, exist 85 in the shaft entering the still at its longitudinal axis. Obviously, this shaft must have an extremely effective packing maintained at all times, within the stuffing boxes, in order to prevent excessive leakage, yet the 90 packing would be subjected normally, to such high temperatures, as would rapidly deteriorate the material thereof. Accordingly, I have provided the simply water-cooling means found in the terminally-bored 95 shaft 18, which entering the stuffing boxes 19, at either end is maintained in relatively cool condition at all times, by the internal flow of water from pipes 22, 22', positioned 100 interiorly of the bored shaft terminals. The details of this feature, and the helicoidal agitator and cleaner, are well shown in Fig. 3 of the drawings.

In order that the coöperation of the additional apparatus herein shown, may be 105 understood, I may now refer to the possibility of operating continuously therewith. After the described operation has progressed, until approximately 10% of the volume of gas oil charged into the still, has 110 been converted into other products boiling between 80° to 350° F., and the Baumé gravity of said products is found to range from 56 to 58 B., as indicated by the hydrometer on samples taken from the end 115 of the pipe entering tank 17, the pump 12 is started. Gas oil thus is continuously pumped in through the line 10, regulated by and through valve 11, entering the still at the front end, at the same time the new 120 products referred to, are conducted off through the vapor line. Any convenient device may be used, such as meters 30, 31, to establish the ratio of a constant quantity of gas oil, entering the still at the front end, 125 and a corresponding quantity of similar products passing off, and collecting in the receiving tank 17.

Having established the quantity entering and leaving the still, the operation is con- 130

tinued until approximately 50% of the volume has been conducted off, when the oil in the still will have reached approximately 24 Baumé gravity. The valve 25, connected

5 by a pipe to the discharge pipe on the bottom, near the rear end of the still, is then operated for the purpose of drawing off the contents, either continuously or periodically; measuring it through a meter 32, 10 after the liquid has passed through the coils 27, submerged in the cooling box 26.

The liquid condensed and collected in tanks 17, may be distilled in the ordinary manner, primarily for its gasoline content, 15 while the heavier distillates therefrom, may be mixed with the contents of tank 29, and re-introduced into the still, for further treatment, if desired, after the carbon has been allowed to settle out. Connected at 33, 20 is an automatic mechanism, which may be used for controlling the continued practice of the prescribed process, but as these steps form no part of my invention, they need not be further referred to herein.

25 It is apparent that the mechanism provided, serves continuously to agitate the contents of the still, and such agitation, moreover, is coupled with the repeated scouring and scraping of the bottom of said still; 30 all of which contribute to the retention of the carbon in its amorphous form, and prevent its adherence to the bottom plates of said still. In addition, thereto, the helicoidal blade 21, may be formed of copper 35 or copper alloy, instead of steel, and may be substituted or augmented by chains or brushes of any material, adapted to afford catalytic action, and therefore promote the chemical re-actions within the still.

40 It will be observed that the shaft 18, in Figs. 3 and 4, is slightly eccentric with respect to the axis of the still 7. This is designed to relieve a large portion of the inner periphery from unnecessary friction and 45 scraping action, through the rotation of the helicoidal blade. Moreover, this blade 21, is somewhat loosely mounted upon the arms 18', so that there is permitted sufficient play for the eccentrically mounted helicoidal 50 member to traverse all of the highly heated portions interiorly of the still, and prevent the deposit of carbon thereon, avoiding the undue friction afforded by the complete peripheral engagement of said helicoidal 55 blade. In Fig. 5, a helicoidal member is shown to be augmented or supplemented in its action, by looped chains 34, attached at intervals to said blade 21. These loops may be alternating in position, and they may be 60 attached upon both sides of the blade, as indicated in the fragmentary view, Fig. 7.

Other means afforded in the brushes 35, arranged in staggered relation upon opposite sides of the helicoidal blade, are indicated in the larger fragmentary view, Fig.

6; which brushes are adapted to scour the inner surface of the still, and assist the blade in removing the deposits of any and all nature from the inner periphery thereof.

Various modifications of the apparatus 70 herein specifically described and shown, may be made without departing from the spirit of my invention, which I desire to protect, together with all such modifications as may be made by mere skill. The process used for 75 explaining the operation of my improved apparatus, is novel, and protection therefor is sought in my application for patent, Serial No. 57,358, filed October 22nd, 1915.

Having now described an apparatus embodying my invention, I claim as new, and desire to secure by Letters Patent, the following:—

1. In apparatus of the class described, the combination with a sealed cylindrical pressure-still, of a longitudinal shaft extending interiorly of the still, and a rotary abrading member loosely mounted for actuation by said shaft and having a portion thereof in continuous engagement with the bottom 85 sheets of the still; said still being set substantially in horizontal position to permit the abrading member to bear upon the bottom of the still, substantially as set forth.

2. In apparatus of the class described, the combination with a sealed cylindrical pressure-still, of a longitudinal shaft extending interiorly of the still, a helicoidal member mounted upon the shaft for rotation 100 interiorly of the still, and chain loops attached adjacent to the edges of said member and depending therefrom for scouring the bottom sheets of the still; said still being set substantially in horizontal position to permit the action of gravity in assisting the 105 scouring operation, substantially as set forth.

3. In apparatus of the class described, the combination with a sealed still, of a stuffing-box, a shaft extending through said stuffing-box interiorly of the still and terminally bored beyond the stuffing-box, a pipe extending within said bore beyond the stuffing-box and a water supply connected with said pipe for cooling the end of the shaft within the 110 stuffing-box, substantially as set forth.

4. The combination with a horizontally supported cylindrical pressure still, of a shaft eccentrically positioned with respect to the axis of the still, and a helicoidal member approximating the full inner diameter of said still and mounted interiorly thereof upon the shaft in engagement with, and bearing constantly upon the bottom sheets of the 115 still, substantially as set forth.

5. The combination with a horizontal cylindrical pressure still, of a shaft eccentrically mounted with respect to the axis of the still, a helicoidal member approximating the diameter of the still and positioned in- 120 125 130

teriorly thereof, and driving members upon the shaft loosely connected with said helicoidal member, adapted to rotate the same in engagement with the bottom sheets of the 5 still, substantially as set forth.

6. The combination with a horizontal, cylindrical pressure-still presenting an even interior bore, of a horizontal shaft extending interiorly of said still, and a rotatable 10 abrading-member approximating the inner diameter of the still and bearing upon its bottom sheets, mounted for actuation by said shaft, substantially as set forth.

7. The combination with a horizontally 15 positioned, cylindrical pressure-still pre-

senting an even interior bore, of a horizontal shaft extending within said still, a rotatable scouring-member approximating the diameter and length of the still, and driving parts upon said shaft loosely connecting the 20 scouring-member for actuation upon the bottom sheets of the still, substantially as set forth.

In testimony whereof I do now affix my signature in the presence of two witnesses.

HORACE B. SETZLER. [L.S.]
